FEELER MECHANISM FOR LOOMS.

1,308,246.

Specification of Letters Patent.

Patented July 1, 1919.

Application filed October 23, 1915. Serial No. 57,587.

To all whom it may concern:

Be it known that I, FRED LACEY, a citizen of the United States, and resident of Lowell, county of Middlesex, and State of Massachusetts, have invented an Improvement in Feeler Mechanisms for Looms, of which the following description, in connection with the accompanying drawings, is a specification, like characters on the drawings representing like parts.

The invention to be hereinafter described relates to feeler mechanisms for looms, and more particularly to that type wherein, upon substantial or practical exhaustion of the filling in the shuttle, the feeler member is adapted to be moved in a direction longitudinally of the filling carrier to initiate filling replenishment, or otherwise affect the loom operation.

20 In this general type of feeler mechanism, the feeler member is usually provided with an end portion adapted to enter the shuttle on the detecting beat-up stroke of the lay, and be prevented from movement in a direction longitudinally of the shuttle by engagement with the filling provided a working supply is present; but when the filling has become nearly exhausted and is no longer capable of resisting the tendency of the 25 feeler to move in said direction, the feeler is permitted to move longitudinally of the shuttle or filling carrier to thereby cause a train of mechanism to become effective to replenish the supply of filling.

30 Where the feeler is normally under the influence of actuating means tending to move it longitudinally of the shuttle or filling carrier, it must be returned to its proper feeling position after it has responded to such means or after such detecting operation. An important feature of the present invention, therefore, consists in means adapted to be engaged at times by a part carried by the feeler as the lay goes back after a detecting 35 beat for restoring or moving the feeler laterally to feeling position. This feature of the invention is embodied in a stationary cam or incline formed as part of or mounted on the feeler stand, which acts upon a member carried by the feeler as the lay retreats and insures proper feeling position of the feeler.

Upon the non-detecting beat-up movement of the lay when the shuttle is not in the box adjacent the feeler member, said member

will not engage the filling in the shuttle and in such case the feeler should be retained in feeling position. A feature of the invention, therefore, consists of means engaged by a part carried by the feeler to hold the 60 feeler in feeling position when the lay makes its non-detecting beat. Another feature of the invention consists in cam means acting in conjunction with the stationary cam to insure restoration of the feeler to feeling position.

These and other features of the present invention will be hereinafter described and then definitely set forth by the claims.

In the drawings:—

70 Figure 1 is a plan view of a feeler mechanism embodying one form of the present invention, some of the loom parts being omitted and others shown in section;

Fig. 2 is a section on the line 2—2, Fig. 1; 75

Fig. 3 is a plan view showing the feeler member as having been moved in a direction longitudinally of the filling carrier, when the filling has become nearly exhausted;

Fig. 4 is a section on the line 4—4, Fig. 1, 80 showing the actuating hammer in its back and front position by dotted and full lines, respectively; and

Fig. 5 is a perspective view showing the general relation of the actuating hammer 85 and the parts adapted to coöperate therewith.

The present invention is especially adapted for application to an automatic loom, wherein filling replenishing mechanism is 90 rendered effective to provide a fresh supply of filling when that in the shuttle in play has become nearly or substantially exhausted, but it may also be employed in connection with some other train of mechanism. 95

In the present embodiment of the invention, the loom frame may be of any usual or desired character, and secured to the breast beam 1, for rocking movement relative thereto is the usual transverse shaft 3. This 100 transverse shaft may be connected, as usual in this type of loom, to suitable means for initiating filling replenishment when said shaft is rocked, all as will be readily understood by those skilled in the art.

Secured to the transverse shaft 3 and extending upward therefrom is the arm 4 having pivotally connected thereto at 5 the arm 6, which arm may, for identification, be hereinafter termed the actuator, because 110

through its movement by the means to be described, it turns or actuates the transverse shaft 3 in opposition to its usual spring-holding means to initiate the replenishing 5 operation.

Pivotedly mounted at 7 upon the actuator 6 is a swing arm 8, the front end portion 9 of which is normally under the influence of a spring for turning said arm upon its 10 pivot contra-clockwise, viewing Fig. 1. In the present instance of the invention, the actuator 6 is provided with a socket portion 10 in which is a spring 11, one end of which is seated upon the part 9 of the arm 8, and 15 if desired, a headed screw 12 may be provided for holding the spring in position, the construction being such that when the arm 8 is free to be moved about its pivotal mounting, it will respond to the spring 11 and turn contra-clockwise, Fig. 1.

The end portion of the arm 8 on the opposite side of its pivotal mounting 7 is provided with a shoulder 13 adapted, under certain conditions to be hereinafter described, 25 to be engaged by a lug 14 extending from an arm 15 connected to the usual weft hammer 16. In order that the lug 14 may be properly adjusted into desired relation with the shoulder 13, the arm 15 may be conveniently 30 secured to the weft hammer 16 adjustably, as by the slot and bolt connection 17.

From the construction described, it will be obvious to those skilled in the art, that if the shoulder 13 of the swing arm is moved 35 by the spring 11 into the path of movement of the lug 14 as the latter moves forward, the actuator 6 will be moved to the front, turn the transverse shaft and initiate filling replenishment.

Extending from the swing arm 8 is a part 40 18 having a web 19 to which is connected one end of a rod 20, the other end of said rod being connected to a projection 21 extending from a feeler member 22. The feeler member 22 is mounted for movement in a direction longitudinally of the shuttle or filling carrier, and in the present instance of the invention is pivotally mounted at 23 on a 45 fixed axis secured to a plate 24 which is itself mounted upon a suitable bracket 25 secured to the loom frame. It may at times be desirable to adjust the plate 24 and parts carried thereby, and to conveniently effect this purpose, the plate 24 is provided with 50 a slot 26 through which extends a bolt 27. From the construction described it will be evident that the feeler member 22 is under control of the swing arm 8 and its actuating spring 11, the action of said spring tending 55 to normally move the feeler member in a direction longitudinally of the shuttle or filling carrier, or to the left, viewing Fig. 1.

The feeler member 22 may be variously formed and provided with a part to engage 60 the filling on the filling carrier to prevent

movement of the feeler member longitudinally relatively to the shuttle or filling carrier when a working or sufficient supply of filling is present and permit such movement responsive to the swing arm and its spring 70 when the filling is nearly exhausted, but in the present instance the feeler member has upwardly projecting portions 28 and 29 through which passes a feeler finger 30 having a serrated or roughened end 31 for engaging the filling, the construction being such that the serrations or roughened end 31 by engagement with a working supply of filling will prevent movement of the feeler member longitudinally of the shuttle or filling carrier, but when the supply has become nearly or substantially exhausted and only enough remains to reach one or more times across the lay, such end will permit such movement of the feeler member in response 80 to the swing arm 8 and its spring.

The feeler finger is under the influence of a light spring to normally project it beyond the end of the feeler member and cause it to pass through the usual openings 32 and 33 90 in the shuttle-box and shuttle, respectively, and contact with the filling 34 in the shuttle. In the present instance the feeler finger 30 is surrounded by the spring 35 one end of which bears upon the projection 29 and the 95 other end upon the shoulders 36 of the finger, the construction being such that on each detecting beat of the lay, the feeler finger will be moved relatively to the feeler member toward the front of the loom, whether a working supply of filling be present or not, and when the lay moves back the feeler finger will be returned to initial position by its spring.

The present invention contemplates that 105 after each call for replenishment due to movement of the feeler longitudinally of the shuttle or filling carrier upon substantial exhaustion of the filling, the feeler be moved in the opposite direction back into 110 feeling position. To this end the relative movement of the feeler member and feeler finger as the lay goes back after a detecting beat is utilized, and means are provided to be effective upon such relative movement 115 of the feeler member and feeler finger, to return the feeler to feeling position. Applicant believes himself to be the first in the art to return or move a feeler of this character longitudinally of the shuttle or filling 120 carrier to feeling position by movement of the feeler finger, and desires it understood that while the drawings herewith, to be further described, show a good, practical form of the invention, the invention itself 125 is not restricted thereto, but may be variously modified within its true scope as defined by the claims.

In the illustrated form of the invention, the feeler finger 30 is provided with a roller 130

37 which may be conveniently mounted upon a pin 38, the construction being such that the roller 37 moves with the feeler finger. Mounted in proper position for coöperation 5 with said roller as it is moved by the finger is a part to return the feeler to feeling position as the feeler finger moves rearwardly. This part may be variously formed, but in the present instance of the invention it 10 comprises a cam 39 suitably supported upon the plate 24 by suitable means such as the arm 40 and screws 41, the construction being such that upon a detecting beat of the lay, if a working supply of filling is present in 15 the shuttle, the feeler finger will be engaged by the filling and moved toward the front of the loom relatively to the feeler member and the feeler as a whole will be prevented from movement longitudinally of the shuttle 20 or filling carrier by the working supply of filling. Under these conditions replenishment of filling will not be initiated, as will be understood. As the lay moves back, the feeler finger will also be moved back 25 by its spring 35, until it is stopped by suitable means, such for instance, as the roller 37 engaging the projection 29 of the feeler member, and the said roller will engage the cam 39 at its flattened end portion 42 which 30 may be preferably formed to resist movement of the feeler to the left, Fig. 1, when the serrated or roughened end of the feeler finger has been disengaged from the filling.

From the construction described, it will 35 be apparent that should the filling have become practically exhausted upon the detecting beat of the lay, the feeler finger 30 will again be moved frontward by engaging the filling carrier substantially as indicated in 40 Fig. 3, and at the same time the feeler will be permitted to move longitudinally of the shuttle or filling carrier in response to the swing arm 8 and its spring. In the following backward movement of the lay, the 45 feeler finger 30 will again be moved rearward by its spring 35 relatively to the feeler member 22, and since at this time the feeler is in the position indicated in Fig. 3, the roller 37 on the feeler finger will engage the 50 cam 39 and riding along such cam in response to the feeler finger spring 35, will serve to move the feeler longitudinally of the shuttle or filling carrier, until the roller 37 has reached the flattened end portion or 55 rest 42 of the cam 39, or in other words, return the feeler to feeling position.

Feeler mechanisms are necessarily delicate in construction and operation, and it may 60 happen at times that the backward movement of the feeler finger under the impulse of its actuating spring 35 might not be sufficient to return the feeler completely to its feeling position. In such cases to insure the complete return of the feeler to its feeling 65 position after a replenishing operation, the

swing arm 8 is provided with a member to engage the projection 14 of the actuator hammer 15 as the weft hammer and, perforce, the actuator hammer move back.

In the present instance of the invention 70 in this respect, the swing arm 8 is provided with a cam member 43, Figs. 1 and 5, having a cam surface 44, adapted to be engaged by the rear bevel edge portion of the projection 14, as indicated in Fig. 5, when the 75 actuator hammer 15 moves rearwardly, the construction being such that after the feeler 22 has been moved longitudinally of the shuttle or filling carrier to effect the initiation of filling replenishment, and the lay 80 has moved backwardly to relieve contact of the feeler finger and the filling carrier, and the cam 39 has acted to return the feeler to feeling position, the projection 14 on the backward movement of the actuator hammer, will engage the cam surface 44 of the cam member 43 and insure that the feeler has 85 been properly moved to feeling position; and if it has not been completely moved to such position, act to complete such movement in 90 the present invention by freeing the roll 37 from the cam surface 39, thus permitting the spring 35 free action to move the feeler finger 30 rearwardly so that the roll 37 may finally rest upon the flattened portion 42 95 of the cam. The feeler finger 30 could be made to return to its proper rearward position by using a stiff enough spring 35, but the described construction or modifications thereof is preferable, because the use of a 100 light spring to act upon the feeler finger is made possible and yet the finger is caused to assume its proper rearward position.

The cam member 43 having the cam surface 44 to act in the manner described may 105 be variously contrived and connected to the swing arm 8, but in the present form of the invention, comprises a plate as indicated in Fig. 5 connected adjustably to the swing arm 8 by suitable means such as the screw or slot 110 connection 45. In order to maintain the cam member 43 in proper position on the swing arm 8, it may have projecting therefrom a flange 46 for engaging the side portion of the arm 8, substantially as indicated 115 in Figs. 1 and 5.

When, on a detecting beat of the lay, the filling has reached a condition of substantial exhaustion, the serrations or teeth 31 on the feeler finger 30 will engage the filling carrier, or the little filling still remaining thereon, and will be permitted under such conditions, to move longitudinally of the shuttle or filling carrier under the action of the swing arm and its spring 11, thereby 120 permitting the swing arm to carry the shoulder 13 thereof into the path of the projection 14 of the actuator hammer, so that as the actuator hammer moves toward the front, it 125 will carry with it the swing arm 8 and, per-

force, the actuator 6 which, through the arm 4, will turn the transverse shaft 3 and initiate filling replenishment.

From the construction described, it will be seen that the invention comprises a single 5 feeler member having a part, such as a feeler finger, which is moved frontwardly on the detecting beat of the lay and which, on resuming its initial position as the lay goes back, acts to return the feeler member to 10 feeling position or move it longitudinally of the shuttle if it has been moved from such position on the detecting beat. This characteristic operation of the feeler is not dependent 15 on the presence of a so-called "bunch" on the filling carrier, and in this respect the feeler mechanism may be advantageously employed whether the filling carrier in the shuttle is provided with a bunch, or not.

It is sometimes necessary to turn the loom 20 by hand without the shuttle in order to find the pick. In such cases, of course, it is desirable that the filling replenishing mechanism shall not be operated. The present invention effects this inoperative condition of 25 the replenishing mechanism under such circumstances by permitting the roller 37 to remain in contact with the cam 39, because there being no shuttle employed, the feeler finger 30 will not be moved forward on the detecting beat-up movement of the lay.

In order that the relative positions of the swing arm 8 and the feeler member 22 may 30 be properly adjusted to operate as hereinbefore described, it is desirable that the connection 20 between these parts be made adjustable, and this is effected in the present instance of the invention, by the turnbuckle 47, although it will be understood that other 40 adjusting means might be employed. It is likewise desirable that the swinging relation of the swing arm 8 and the pivotally-mounted feeler member 22 may be properly adjusted, and to this end the web 19 of the 45 swing arm 8 and the part 21 of the feeler member 22 are each provided with a plurality of openings 48 adapted to receive the end portion 49 of the connecting rod 20. By adjusting the ends of the connecting rod 20 into the different openings 48, it will be evident, of course, that the relative swinging 50 movement of the swing arm and feeler may be variously changed to cause the swinging movements of the swing arm and feeler to 55 properly relate the parts to their co-operating elements.

What is claimed is:—

1. A feeler mechanism for looms, comprising 60 a feeler member, a feeler finger mounted on said feeler member for movement with and relative thereto, means for moving the feeler member longitudinally of the shuttle to initiate filling replenishment when the filling has become substantially exhausted, 65 and means rendered effective by movement

of the feeler finger relative to the feeler member for returning the feeler member laterally to feeling position.

2. A feeler mechanism for looms, comprising 70 a feeler member pivotally mounted to swing about a fixed axis in a direction longitudinally of the filling carrier upon detection of substantial exhaustion of the filling in the shuttle, a feeler finger mounted on and movable relatively to the feeler member, 75 and means including a part carried by the feeler finger for returning the feeler member to feeling position by movement of the feeler finger relative to the feeler member.

3. A feeler mechanism for looms, comprising 80 a feeler member mounted for movement longitudinally of the shuttle upon the occurrence of substantial exhaustion of filling, a feeler finger mounted on and movable relatively to the feeler member, a cam, and a part 85 carried by the finger adapted to engage the cam as the finger moves rearwardly relative to the feeler member after a detecting beat to move the feeler member laterally.

4. In a feeler mechanism for looms, the 90 combination of a feeler member, a feeler finger mounted thereon to feel for the filling in the shuttle and be moved forward thereby, means for returning the feeler finger to its rearward position as the lay goes back, 95 means including a part rendered effective by rearward movement of such finger to return the feeler member toward feeling position, and means normally tending to move the feeler member and finger in a direction longitudinally of the shuttle.

5. In a feeler mechanism for looms, the combination of a feeler member pivotally mounted to turn about a fixed axis, means for moving the feeler member about said 105 axis in a direction longitudinally of the shuttle, a feeler finger movable with the feeler member, a spring normally acting to project said feeler finger rearwardly relative to the feeler member, and means rendered 110 effective by rearward movement of the feeler finger for insuring the return of the feeler member to feeling position after it has been turned on its fixed axis.

6. In a feeler mechanism for looms, the 115 combination of a feeler mounted for movement toward and from the front of the loom, means for engaging the feeler as it moves rearwardly to restore it to feeling position after it has been laterally displaced, an actuator and actuating hammer, a cam member between the actuator and actuator hammer to draw the feeler laterally when the lay has gone back and insure the return of the feeler to proper feeling position.

7. In a feeler mechanism for looms, the combination of a feeler member, means acting upon the feeler member in a direction tending to move it longitudinally of the shuttle, a feeler finger yieldingly mounted 130

- thereon, means, including a part carried by the feeler finger, rendered effective by rearward movement of such finger relatively to the feeler member to return the feeler member toward feeling position, a cam member, connections between the cam member and feeler member, and means for acting upon the cam member to insure complete return of the feeler member to feeling position.
- 5 10. In a feeler mechanism for looms, the combination of a feeler member mounted for movement longitudinally of the shuttle when the filling is substantially exhausted, an actuator, a swing arm connected to the actuator, a connector pivotally united to the feeler member and swing arm, and means for varying the distance of the pivotal points of the connector from the ends of the feeler member and swing arm to change the relative movements transmitted from one to the other.
- 15 9. In a feeler mechanism, the combination of a feeler member pivotally mounted to swing in a direction longitudinally of the shuttle upon substantial exhaustion of filling, an actuator, a swing arm pivotally connected thereto, a rod connecting the feeler member and swing arm, and means for shifting the points of connection to different distances from the pivotal points of the swing arm and feeler member to change the degree of relative movements transmitted by the said rod between the swing arm and feeler member.
- 20 10. In a feeler mechanism for looms, the combination of a feeler member mounted for movement longitudinally of the shuttle upon substantial exhaustion of filling, a feeler finger mounted yieldingly upon the feeler member, a stationary rest, and a part carried by the feeler finger to engage the rest and hold the feeler member from movement longitudinally of the shuttle when the feeler finger is in rear or feeling position.
- 25 11. In a feeler motion for looms, the combination of a feeler having a filling engaging part to feel for the filling in the shuttle as the lay beats up and be moved frontward thereby, means for returning the said part to rearward position as the lay moves back, means for moving the feeler in a direction longitudinally of the shuttle upon detection of substantial exhaustion of filling, and means rendered effective by movement of said part to rearward position for returning the feeler to feeling position.
- 30 12. In a feeler mechanism for looms, the combination of a feeler member, means tending to move the feeler member longitudinally of the shuttle on a detecting beat, a cam, and a part mounted on the feeler member for coacting with said cam and adapted to be moved relatively thereto on the detecting beat of the lay to free the feeler member from the control of the cam and to engage
- 35 40 45 50 55 60 65 70 75 80 85 90 95 100 105 110 115 120 125 130
- said cam on the following backward movement of the lay to place the feeler in feeling position.
13. In a feeler motion for looms, the combination of a feeler having a filling engaging member mounted on the feeler for movement longitudinally thereof by the frontward push of the filling or carrier as the lay moves frontward on a detecting beat, means normally acting to move the feeler in a direction longitudinally of the shuttle, a fixed projection adapted to be engaged by a part of the filling engaging member of the feeler to prevent movement of the feeler in response to said normally acting means when said feeler engaging member is in rearward position on said feeler and to permit movement of the feeler in response to said means when the said part of the filling engaging member is moved frontward and out of engagement with said fixed projection.
14. In a feeler motion for looms, the combination of a feeler, means normally acting to move it in a direction longitudinally of the shuttle, a filling engaging member mounted for longitudinal movement on said feeler, a spring normally forcing said member into rear position relative to the feeler but permitting it to yield frontward on a detecting beat of the lay, a lug or projection secured in fixed position, a part connected with the filling engaging member of the feeler and engaging said fixed lug or projection when the said member is in rear position to hold the feeler from movement responsive to said normally acting means and movable from engagement with said fixed lug or projection when said filling engaging member of the feeler is moved frontward on a detecting beat.
15. A feeler mechanism for looms, comprising a feeler to feel for the filling in the shuttle, a fixed cam, and a part carried by the feeler adapted to engage the fixed cam as the lay goes back after a detecting beat, and restore the feeler laterally to feeling position, and means acting through the feeler after it has reached rearward position to insure the return of the feeler laterally to feeling position.
16. In a feeler mechanism for looms, the combination of a feeler stand, a feeler mounted thereon for movement longitudinally of the shuttle when the filling is substantially exhausted on a detecting beat, a cam or inclined member carried by the feeler stand, a part mounted on the feeler to engage said member as the lay goes back after an indication of substantial exhaustion of filling to restore the feeler laterally to feeling position, and means for drawing the feeler laterally to relieve the frictional engagement of the part mounted on the feeler and the cam or inclined member to insure the return of the feeler to feeling position.

- 2
17. In a feeler mechanism for looms, the combination of a feeler stand, a feeler mounted thereon for movement longitudinally of the shuttle when the filling is substantially exhausted on a detecting beat, a fixed member having an inclined portion for restoring the feeler to feeling position, a part carried by the feeler adapted at times to engage the fixed inclined member as the lay goes back after a detecting beat, and means for moving the feeler laterally to relieve the pressure against the inclined member to insure complete return of the feeler to feeling position.
18. In a feeler mechanism for looms, the combination of a feeler stand, a feeler member having a filling engaging end and mounted directly on the stand for movement longitudinally of the shuttle when the filling is substantially exhausted, a fixed cam having an incline and a rest, and a part carried
- 5 by the feeler member adapted at times to engage the fixed cam as the lay goes back after a detecting beat to restore the feeler laterally to feeling position and to reengage 25 said rest when the feeler is in feeling position.
19. In a feeler motion for looms, the combination of a feeler stand, a feeler mounted thereon for movement longitudinally of the shuttle when the filling is substantially exhausted, a fixed cam and a rest, a part carried by the feeler to ride along the cam and engage the rest as the lay goes back, said rest preventing movement of the feeler longitudinally of the shuttle until the part carried by the feeler has been moved forward past the rest.
- 10 20 30 35
- In testimony whereof I have signed my name to this specification.

FRED LACEY.
